SIMPLIFIED COIN-WRAPPING MACHINES

Harvey C. Nesbitt, Calgary, Alberta, Canada

Application February 3, 1954, Serial No. 407,944

12 Claims. (Cl. 53—213)

2

My invention relates to a coin-wrapping machine, and the object is to provide such a machine that will rapidly and securely complete the work of wrapping coins in packaged rolls, and in a semi-automatic manner.

Parts of this machine may be so adjusted that rolls of any denominations of coins may be handled in batches of one such denomination at a time, and continuous coin-wrapping runs made for that particular denomination.

A further object is to facilitate handling of large quantities of any one denomination of coins in a time-saving manner, and in my invention the machinery to accomplish this is extremely simple in comparison with conventional coin-wrappers, and it may be manufactured very economically when compared with other machines for similar purposes.

This machine is compactly composed as to its various parts, and as illustrated and hereinafter described is slidably activated by hand, or it may be readily electrically driven by a motor by the addition of a few necessary parts.

In the drawings which illustrate the embodiments of the invention,

Figure 1 shows an elevational cross sectional view of the machine on lines 1—1 in Figure 3.

Figure 2 is a view of a portion of Figure 1 showing wrapping paper starting device in operational position.

Figure 3 is a plan view of the machine.

Figure 4 is an enlarged detail of roller for carriage supporting cross bars.

Figure 5 is an enlarged detail of adjustable coin-supporting elements.

Figure 6 is an enlarged detail of the ramp and associated roller to operate the paper starting mechanism.

Figure 7 is an enlarged side elevation of the block disengaging mechanism showing the wheel just contacting the bevelled ends.

Figure 8 is a view similar to Figure 7, but showing the bar advanced with respect thereof.

Figure 9 is sectionalized view on line 9—9 of Figure 3.

Figure 10 shows an end elevational view looking towards the right end of Figures 1 and 3.

Figure 11 is an enlarged detail fragment of coin wrapping means with paper starting device, and coin-supporting rollers.

Figure 12 is an enlarged detail of hinged ramp and contacting roller to operate means for advancing wrapping papers.

Figure 13 is an enlarged detail of the wrapping starting device.

In the drawings the numeral 1 refers to each of two upright side plate members supporting the machine, to the top longitudinal edge of each of which is affixed a channel sectioned member 2 with flanges facing inwardly of the machine. The ends of this supporting frame are closed by transverse plates 3 and 4 with the exception that the one at the feed-in end to the left in Figure

1 where the top edge is spaced below the top level of the side channels, and also that the plate 4 at the discharge opposite end the bottom edge of this plate is spaced above the bottom of the machine, through which space wrapped coins are to be discharged.

The roll of coins 5 in this coin-wrapping machine is placed transversely thereof, and rests on at least three transverse rollers 6 covered with deformable material. Between coin and rollers a coin-wrapping sheet of paper 7 is inserted flatwise passing from a tray 8 supported on transverse plates 9 bridging the side plates 1. The coins are held erect during wrapping, and also held in place, by adjustable transversely disposed rods 10, and are braced between these two rods, the rods being bearably mounted in blocks 11 on one side member and 11a on the other side member, attached to the outer faces thereof. These same rods pass threadably into blocks 12 and 12a respectively and face on the said blocks 11 and 11a, and have adjustable nuts 13 on their outer ends. Adjustable slideable bars 14 for the support of the rollers 6 are slidably mounted in slotted arcular shaped keeper members 15 attached to the inner faces of the side members 1. Pressure is maintained between rollers 6 and the paper-enclosed coin roll 5 by means of springs 16 enclosing rods 17 extending from each said bar 14. The ends of these rods are supported in apertured brackets 18 attached to the inner faces of sides 1. Nuts 19 on the ends of these rods are the adjusting members therefor.

With the coins cradled on the rollers 6 the parts for wrapping the paper therearound consist of a carriage plate 20 indirectly supported on transverse bars 21, 22, and 23, each said bar having a free turning roller 24 at its ends. These end rollers travel in tracks 25 which are affixed outboardly and within the channel members 2 to the top edges of the side walls 1. As the carriage assembly plate 20 moves from right to left (Figures 1 and 2) a paper-starting plate 26 comes in contact with the extending end of the paper 7 nearest to the coins in place on the rollers 6, and carries same over the coin roll 5. The movement of the carriage is accomplished by gripping a handle 27 mounted on top of the bar 23 and braced by a bar 27a on to the bar 22.

The coactivating mechanism in the wrapping process consists of a free turning roller 28 attached perpendicularly to an arm 28a attached to the spindle of the roller 28 and mounting same, the roller running on top of one of the channel members 2. The other end of this arm 28a is attached to a transverse shaft 29 supported on two blocks 30 on the said transverse bar 21. Two paper-starting plate bars 31 are affixed to the cross shaft 29 and swing with it together with the arm 28a, and the roller 28 rides up and down the track of a ramp 32 mounted also on this same side channel member 2. The said ramp is pivoted by a pin 33 mounted on this side member, and as roller 28 contacts the ramp this actuates the starting plate bars 31, each plate bar having an associated thrust spring 34 enclosing a rod 35 passing down through it towards and connecting with the said paper-starting plate 26, which is therefore in indirect connection with the bars 31. These rods 35 are slideable within the heads of the bars 31. As the carriage is carried further to the left (Figures 1 and 2) the carriage plate 20 comes in contact with the coin roll 5 now covered in readiness with the paper 7, which paper is held firmly and closely against the coin roll by the action of the springs 34 pressing down on the paper-starting plate 26. The carriage plate 20 forces the coin roll against the bed rollers 6, and by friction causes the roll to rotate in an anticlockwise direction as referred to

Figure 1, thus wrapping the paper tightly around the roll of coins.

At this time the free roller 28 oversteps the forward edge 32a of the ramp 32 and drops to a starting position on top of the channel 2 on the ramp side, which action raises the paper-starting plate 26 back to its original position, the paper having made one complete turn to encircle the coins, and the said plate has completed its purpose.

As the right to left movement is continued the whole of the sheet of paper has been wrapped around the coins, and at this point a free wheel 36 on a point-retracting rod 37 assembled with blocks 11 and 12 on the one side of the machine contacts a plate 38 supported on the bars 20 and 23, which plate has a bevelled end 39 at its front end. This action forces the free block 12 to the right or away from the block 11 (Fig. 9).

With reference to the travel of the roller 28 relatively with the ramp 32, as soon as the roller passes over the end 32a of the ramp, it returns under the ramp, lifting a hinged end portion thereof 32b. The hinged end then rests normally in place on the top of channel 2 after the passage of the roller thereunder.

A threaded gear rack 40 (Fig. 9) is attached to this free block 12 and rotates a fixed gear 41 which causes a gear rack 42, attached to the free block 12a, to move outwardly away from the frame, and thus withdraws the coin-supporting rods 10 so that they are clear of paper folding rollers 43. Plates 44 supporting these rollers are adjustably mounted on the rear or right end of the carriage 20 by means of pins 45 slideable in slots cut in these blocks 44. These rollers therefore turn freely in relation with the said blocks 44. The rollers turn freely in holes in the blocks and are attached to the carriage plate 20 by means of pins 45, said pins being slideable in slots cut in the said blocks.

As the carriage 20 continues to travel from right to left the paper folding rollers 43 come in contact with the ends of the paper sheet which ends protrude from each side of the coin roll. (The said rollers are spaced one third of the circumference of a coin roll), and are folded very tightly against the ends of the roll in three folds on account of the set revolutions of the coin roll and the exact positioning of the folding rollers 43. Tension springs 46 are disposed between the blocks 44 which supply the necessary pressure to insure this tight folding action, and also sufficient expansion to provide for a longer than average coin roll, which might possibly be the case due to new or thicker coins than are conventionally in circulation.

As the carriage 20 travels still further to the left its plate passes over the securely packaged coins, and an inked rubber stamp 47 automatically contacts the roll for name printing etc. At this point the carriage has reached its limit of travelled distance and is ready for the return to its starting position again. In this returning action the springs 16 force the packaged coins up, and as the carriage is moved to the right (Figures 1 and 2) the packaged and stamped coin roll is pushed from the coin bed rollers 6 and rolls down the curved face of a chute 48, and discharges through an opening at the bottom of the end wall or plate 4, this opening being shown at 49. As the return of the carriage begins a free roller 50 (Figure 12), attached to a crank arm 51 on a shaft 52 contacts a ramp 53 attached to one side member of the frame plate 1, the ramp being hinged by a pin 54 for said attachment and overbalances thereon. The shaft 52 is bearably supported on two blocks 55 mounted on the carriage 20. This contact forces a rubber paper finger 56 down through an aperture 57 in the carriage plate 20, and one sheet of the paper is drawn from the top of the paper stock 7 on the tray 8, and is carried over the roller bed 6. As the roller 50 passes beyond the ramp 53 this rubber paper finger 56

returns to normal position as roller 50 slides down the ramp again, thus releasing paper in a correct position for reception of the next roll of coins.

As soon as the bevel edge of 38, that is the point 39, withdraws from the wheel 36 tension springs 58 connecting the two blocks 11 and 12, and also the two blocks 11a and 12a, draw each coin-supported rod 10 back to its original position. As the carriage 20 completes the return movement to the extreme right position (Figures 1 and 3) the rubber stamp 47 contacts an inking pad 59 which is mounted on the coin-delivery end of the machine body, thus inking said stamp in preparation for the next roll on the movement of the carriage leftwise. Finger 56 is spring loaded by means of bow spring 60 anchored to block 55.

What I claim as my invention is:

1. A device for wrapping rolls of coins comprising in combination with supporting framework therefor, a carriage adapted to be reciprocated within said framework, spaced and parallel guides attached to the upper sides of said framework, said carriage being supported within said guides, said carriage including a transversely situated carriage plate, a set of coin roll supporting rollers mounted transversely within said framework, resilient means mounting said rollers for limited movement in a plane normal to the axis of said rollers, a coin wrapper tray mounted transversely in advance of said set of rollers, means coacting with said carriage and mounted thereon, adapted to position an associated coin wrapper from said tray upon said rollers, means also on said carriage adapted to initiate the rolling of said wrapper around the associated roll of coins, said carriage plate being adapted to engage the upper surface of said coin roll, thereby completing said wrapping process as said carriage is moved along said framework, and further means associated with said carriage adapted to fold in the ends of said wrapper adjacent the ends of said coin roll.

2. A device for wrapping rolls of coins comprising in combination with supporting framework therefor, a carriage adapted to be reciprocated within said framework, spaced and parallel guides attached to the upper sides of said framework, said carriage being supported within said guides, said carriage including a transversely situated carriage plate, a set of coin roll supporting rollers mounted transversely within said framework, a coin wrapper tray mounted transversely in advance of said set of rollers, means coacting with said carriage and mounted thereon, adapted to position an associated coin wrapper from said tray upon said rollers, means also on said carriage adapted to initiate the rolling of said wrapper around the associated roll of coins, said carriage plate being adapted to engage the upper surface of said coin roll, thereby completing said wrapping process as said carriage is moved along said framework, further means associated with said carriage adapted to fold in the ends of said wrapper adjacent the ends of said coin roll, and further means on said framework adapted to hold said coin roll erect prior to the wrapping thereof.

3. The device according to claim 1 in which said carriage consists of a substantially rectangular plate, rollers mounted transversely on the longitudinal edges of said plate, said rollers adapted to engage said guides.

4. The device according to claim 1 in which said coin roll supporting rollers are each mounted transversely for rotation between pairs of bars, said bars being mounted for limited reciprocation within brackets secured to said framework, the lower ends of said bars being spring loaded so that said rollers are normally in the uppermost position, said set of rollers being positioned so that when viewed in cross-section, a substantially semi-circular recess is formed by said rollers for the reception of said coin rolls.

5. The device according to claim 1 in which said coin wrapper positioning means consists of a coin wrapper

contacting finger mounted upon said carriage and extending downwardly therethrough, said finger being secured to one end of a crank arm, also mounted upon said carriage, a roller upon the opposite end of said crank arm, and a ramp upon said framework engageable by said roller, and adapted to move said finger downwardly when same is adjacent said coin wrapper tray.

6. The device according to claim 1 in which said means adapted to initiate the rolling of said wrapper consists of a spindle mounted transversely upon said carriage, forwardly therefrom, an arm also secured to said spindle and extending rearwardly therefrom, a roller upon one end of said arm, a ramp upon the side of said framework engageable by said roller and a paper starting plate mounted upon the forward ends of said arm, said ramp being positioned to move said paper starting plate downwardly, as same approaches the associated roll of coins, said ramp also permitting said paper starting plate to be elevated after said initiation of said wrapping.

7. The device according to claim 1 in which said means to fold the ends of said wrapper consists of a plurality of rollers vertically mounted upon the longitudinal edges of said carriage, said rollers being mounted upon blocks secured to said carriage for limited transverse movement thereon, said rollers being adapted to contact the ends of the wrapper extending beyond said roll of coins and to fold same inwardly against said ends.

8. The device according to claim 2 in which said means to hold said coin roll erect prior to the wrapping thereof consists of a pair of transversely disposed rods mounted for limited transverse movement upon said framework, the inner ends of said rods being adapted to bear against the ends of said coin roll, blocks upon said framework within which said rods are mounted and cam means on said carriage adapted to cooperate with said rods to disengage same from said coin roll immediately prior to the ends of said wrapper being folded.

9. The device according to claim 2 in which said carriage consists of a substantially rectangular plate, rollers mounted transversely on the longitudinal edges of said plate, said rollers adapted to engage said guides, said coin roll supporting rollers being each mounted transversely for limited reciprocation within brackets secured to fit the framework, the lower ends of said bars being spring loaded so that said rollers are normally in the uppermost position, said coin roll supporting rollers being positioned so that when viewed in cross-section, a substantially semi-circular recess is formed by said rollers for the reception of said coin rolls.

10. The device according to claim 2 in which said coin wrapper positioning means consists of a coin wrapper contacting finger mounted upon said carriage and extending downwardly therethrough, said finger being secured to one end of a crank arm, also mounted upon said carriage, a roller upon the opposite end of said crank arm, and a ramp upon said framework engageable by said roller, and adapted to move said finger downwardly when same is adjacent said coin wrapper tray, said means adapted to initiate the rolling of said wrapper consisting of a spindle mounted transversely upon said carriage, forwardly therefrom, an arm also secured to said spindle and extending rearwardly there-

from, a roller upon one end of said arm, a ramp upon the side of said framework engageable by said roller and a paper starting plate mounted upon the forward ends of said arm, said ramp being positioned to move said paper starting plate downwardly, as same approaches the associated roll of coins, said ramp also permitting said paper starting plate to be elevated after said initiation of said wrapping.

11. The device according to claim 2 in which said means to hold said coin roll erect prior to the wrapping thereof consists of a pair of transversely disposed rods mounted for limited transverse movement upon said framework, the inner ends of said rods being adapted to bear against the ends of said coin roll, blocks upon said framework within which said rods are mounted and cam means on said carriage adapted to cooperate with said rods to disengage same from said coin roll immediately prior to the ends of said wrapper being folded, said carriage consisting of a substantially rectangular plate, rollers mounted transversely on the longitudinal edges of said plate, said rollers adapted to engage said guides, said coin roll supporting rollers being each mounted transversely for limited reciprocation within brackets secured to said framework, the lower ends of said bars being spring loaded so that said rollers are normally in the uppermost position, said set of rollers being positioned so that when viewed in cross-section, a substantially semi-circular recess is formed by said rollers for the reception of said coin rolls.
12. The device according to claim 2 in which said means to hold said coin roll erect prior to the wrapping thereof consists of a pair of transversely disposed rods mounted for limited transverse movement upon said framework, the inner ends of said rods being adapted to bear against the ends of said coin roll, blocks upon said framework within which said rods are mounted and cam means on said carriage adapted to cooperate with said rods to disengage same from said coin roll immediately prior to the ends of said wrapper being folded, said coin wrapper positioning means consisting of a coin wrapper contacting finger mounted upon said carriage and extending downwardly therethrough, said finger being secured to one end of a crank arm, also mounted upon said carriage, a roller upon the opposite end of said crank arm, and a ramp upon said framework engageable by said roller, and adapted to move said finger downwardly when same is adjacent said coin wrapper tray, said means adapted to initiate the rolling of said wrapper consisting of a spindle mounted transversely upon said carriage, forwardly therefrom, an arm also secured to said spindle and extending rearwardly therefrom, a roller upon one end of said arm, a ramp upon the side of said framework engageable by said roller and a paper starting plate mounted upon the forward ends of said arm, said ramp being positioned to move said paper starting plate downwardly, as same approaches the associated roll of coins, said ramp also permitting said paper starting plate to be elevated after said initiation of said wrapping.
